UNITED STATES PATENT OFFICE.

SOL W. LUNDIN AND JOSEPH FRIEDMAN, OF NEW YORK, N. Y.

BATHING-SHOE.

1,835,287.

Specification of Letters Patent. Patented Mar. 30, 1920.

Application filed October 24, 1919. Serial No. 333,107.

To all whom it may concern:

Be it known that we, SOL W. LUNDIN and JOSEPH FRIEDMAN, citizens of the United States and Russia, respectively, and residents of the city of New York, in the county and State of New York, have invented certain new and useful Improvements in Bathing-Shoes, of which the following is a specification.

10 The present invention relates to bathing shoes, having a fabric upper and sole of leather or other suitable material secured thereto by marginal stitches.

15 The main object of the invention is to provide a shoe of this character, wherein a flat, unmolded sole is attached in such a manner to the upper that the seam, uniting the sole and upper, is prevented from being cut by sand or rough surfaces traversed by 20 the wearer.

Another object of the invention is to so arrange the seam that it is disposed wholly outside of the upper, so as not to inconvenience the wearer, the arrangement being 25 such that the seam is entirely concealed from view.

A still further object of the invention is to so construct the seam that it prevents sand from gaining access to the shoe.

30 With these and other objects in view, which will more fully appear as the nature of the invention is better understood, the same consists in the combination, arrangement and construction of parts hereinafter 35 described, pointed out in the appended claims and illustrated in the accompanying drawings, it being understood that many changes may be made in the size and proportion of the several parts and details of 40 construction within the scope of the appended claims without departing from the spirit or sacrificing any of the advantages of the invention.

One of the many possible embodiments of 45 the invention is illustrated in the accompanying drawings, in which:

Figure 1 is a side elevation of a shoe constructed in accordance with the present invention; and Fig. 2 is a sectional detail of 50 a portion of the shoe, on a larger scale.

Referring to the drawings, the numeral 10 designates the upper of the shoe, which may be of any suitable fabric, for instance duck or canvas. The sole 11 is cut flat from 55 a suitable piece of leather or like material,

it being connected along its edge by a line of stitches 12 with the upper, said line of stitches serving at the same time to attach to the two elements mentioned a strip 13 of flexible leather or other suitable material. 60 The three elements are united by a single operation, after which the strip is turned back upon itself, its upper edge being sewed to the upper 10 by a line of stitches, indicated at 14. By turning the strip 13 back 65 upon itself, the seam 15, that is formed by uniting the three elements of the shoe, is turned upward, as clearly shown in Fig. 2 of the drawings, and thereby placed between the upper and the strip 13. In this 70 manner the said seam is concealed from view, is protected from being cut by sand or rough surfaces traversed by the wearer, and does not cause inconvenience to the wearer, the foot coming into contact with 75 the upper only, as the upper is disposed between the foot and the said seam.

The bathing shoe or slipper herein described may be manufactured on a commercial scale, or in other words it is not so difficult to produce as to be beyond the reasonable cost of such an article, and yet it is 80 strong and durable in use, and has its upper united with the other elements of the shoe along two parallel lines, so that the said 85 upper has no tendency to rip or break away from the sole.

What we claim is:

1. A bathing shoe comprising a flat unmolded sole, an upper, and a separate strip 90 of material having one edge stitched to said sole and upper and having its other edge secured to said upper only, the seam formed by stitching together said sole, upper and strip being disposed outside of said upper 95 and concealed from view by said strip.

2. A bathing shoe comprising a flat unmolded sole, an upper, and a separate strip of material, one edge of said strip being stitched to said sole and upper with an upturned seam that is disposed outside of said upper, and the other edge of said strip being stitched to the upper only, said strip overlapping said seam. 100

Signed at New York, in the county of 105 New York and State of New York, this 20th day of August, A. D. 1919.

SOL W. LUNDIN.
JOSEPH FRIEDMAN.
